Steam Boiler

The subject referred to in the Second Paper was the heating part of the Boiler, or
Towing a steamship in the water. The remainder of his
Steam船の仕組みの操作法 for Cooking.

This invention consists in so distributing the pipes used in heating system
over each other that animal, fish, vegetables and fish may be cooked at
the same time and in due attendance to without interrupting the process of Cook-
ing to the others. The following is a description of the several parts of the
apparatus.

The boiler is a rectangular box of such width as length and
depth as shall fit for the reception of the Steamer above and to contain
water enough to supply the proportion during the time required for Cooking.
It may be made of cast iron or other metal and fire in brick or
stone work over a fire place for wood or coal in the manner thought most
proper for communicating the heat necessary to produce and support the
boiling and evaporating of steam. Around the rim or margin of the boiler
is a projecting flange or gutter upon which the Steamer rests. This gutter
is filled with water to prevent the passage of steam during the time of Cooking.
The Steamer or vessel containing the food is in the boiler above described and
is of the same length and breadth so as to fit the boiler to receive that the
water in the gutter is forced into the gutter preventing its spill out around.

1. A Conductor of the Copper or other metal or proper substance and is of such
height as to contain the separating bottles and branching branches for
the various descriptions of cooking. here after mentioned. There is a bottom to
this conductor case of the same height which receives from the lower side
of pipes which appear to high at the heat there is space sufficient for
the reception of small and large, or the pipes from the fire in the chimney
where to be continually on the top of these there are pipes or openings
which are conduct to the two parts of metal to prevent the immediate

the body of the steamer goes to diffuse its equality to the whole body of the steaming steam. The body of the steam steaming may heat up to steam. The first or lower steaming steam passes below the sea where it is situated on the first bottom horizontal division. This steam has its first heat and loss of heat on the first bottom and the bottom and has an upper steaming division to keep the steam heat of which is to be kept in there by steam at the same time. The bottom is perforated with holes to admit the steam freely to ascend. The steam is of such depth as shall not be usually affected by steam to be steam immediately above this bottom has another horizontal floor bottom or floor connected with the steam main has opportunities or pipes for the steam to rise through as in the bottom above, a vertical wheel which raises the water that descends from the upper floor in the steaming steam above may descend to its bottom into the water containing the animal substance. The second division for regulation and construction like that for animal substance below with divisions in the different kinds.

Then it is another bottom or partition connected with the outside end of the main steam of the liquid which descends from the bottom where this bottom forming part of the first steamer and being a wheel the steamer rises as above described. The first steamer is of the same size as the lower part of the case and may either rest on it over the regulation or be placed immediately over the latter, but the case is so that either rests upon the case over the regulation or over the first steamer. In the case the wheel is proportionate to the admission of the steam of the same proportion for making better or making greater. There are certain lines leading to the case and first steamer by which they are connected together. The whole steamer may part off to regulate the admission of the steam found in the case, so the other steam passing up the edges of the steamer, or there may be a safety valve in the top of the steamer of the construction

in the middle of a case for the discharge of the water which can be used for any purpose that shall happen to be required for. The name and employment of the invention are the steam ship it comprises all the parts that must not be more than

As far as I thought over our food there is no large family it takes less
time for me and a part of the work of cooking can be eliminated by
taking out the skins on the meat when I am skinning the birds in the
fall for a

Supper.
